United States Patent Office

Des. 222,294
Patented Oct. 12, 1971

222,294

STRINGED MUSICAL INSTRUMENT

Walter J. Pelensky, 19C Manheim Gardens,
Philadelphia, Pa. 19144

Filed Aug. 31, 1970, Ser. No. 24,778

Term of patent 14 years

Int. Cl. D17—03

U.S. Cl. D56—1

Fig. 1

Fig. 3

Fig. 2

FIG. 1 is a perspective view of a stringed musical instrument, specifically a plucked Ukrainian Kobzyna of the Cittern Class, showing my new design;

FIG. 2 is a face view; and

FIG. 3 is a side elevational view thereof.

Portions of the drawings are shaded to indicate contrast in appearance.

I claim:

The ornamental design for a stringed musical instrument, as shown and described.
